[57] CLAIM

The ornamental design for a fountain dispenser merchandising system, as shown and described.

DESCRIPTION

FIG. 1 is a top, front, right side perspective view of a fountain dispenser merchandising system showing our new design;

FIG. 2 is a view identical to FIG. 1 but without any fountain dispenser present;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIGS. 1,2,3,5, and 6 are for illustrative purposes only and form no part of the claimed design.
